UNITED STATES PATENT OFFICE.

JAMES D. FRARY, OF BRIDGEPORT, CONNECTICUT.

TABLE-CUTLERY.

SPECIFICATION forming part of Letters Patent No. 269,276, dated December 19, 1882.
Application filed October 2, 1882. (No model.)

To all whom it may concern:

Be it known that I, JAMES D. FRARY, of Bridgeport, in the county of Fairfield and State of Connecticut, have invented new Improvements in Table-Cutlery; and I do hereby declare the following, when taken in connection with the accompanying drawings and the letters of reference marked thereon, to be a full, clear, and exact description of the same, and which said drawings constitute part of this specification, and represent, in—

Figure 1, a side view of a knife; Fig. 2, the blank from the blade and tang; Fig. 3, one of the scales detached; Fig. 4, a transverse section through the tang and scales as prepared for introduction into the mold; Fig. 5, a transverse section of the complete handle.

This invention relates to an improvement in the manufacture of metal-handled table-cutlery, the object being to produce a strong and durable handle, presenting a white or soft metal surface, which may be readily electro-plated, and yet make the handle hollow, so as to avoid the heavy and clumsy handle when cast solid.

Metal handles have been made hollow by striking up scales in sheet metal, soldered together, and secured to the tang; but such construction makes a handle so weak that it is easily jammed and defaced.

My invention, whereby the difficulties in previous constructions handles of metal are overcome, consists in making the blade and tang of sheet metal, the tang of substantially the outline of the handle, but somewhat less in extent, then attaching to opposite sides of this flat sheet-steel tang thin struck-up scales, which form a core upon which metal may be cast to give the requisite shape and ornamentation to the handle, as more fully hereinafter described.

I first cut the blank, as seen in Fig. 2, from sheet-steel, the tang A being a continuation of the blade B—that is, in one and the same piece—and in the usual manner of cutting blades and tangs from sheet-steel. The blade is ground or struck in the usual manner to give it the required sharp edge, the tang of

the same general outline as the finished handle, but less in extent. Upon each side of the flat tang A, I place a scale, C. These scales are cut from sheet metal, of a shape and size substantially corresponding to the tang, as seen in Fig. 3. These are struck up from the inside outward to give the required swell, and are secured upon each side of the tang A, as seen in Fig. 4. These may be soldered, or any temporary arrangement may be made to hold them in place on the tang. The scales should fit closely upon the tang at their edges.

The mold is prepared corresponding to the finished handle. The extent or size of the tang and scales seen in Fig. 4 is less than that of the finished handle, and is laid into the mold, the scale and tang forming, as it were, a core in the mold. Then into the mold white-metal or other suitable metal is poured, flowing over the outer surface of the scales so as to form an outer surface, D, as seen in Fig. 5. This outer surface corresponds to the mold prepared for casting the handle, and may be of any desirable shape or ornamentation, with or without the bolster. By this construction the handle is made hollow—is strengthened by the tang, so as to prevent bending or breaking. The scales support the soft-metal surface, so as to prevent its being jammed or injured in use, the scales sustaining the outer surface against any blows which may be brought upon it. It is stronger than a cast soft-metal handle or a simple scale handle. It is lighter than the cast-metal handle can be made, because it is hollow, and is very little heavier than the useless struck-up sheet-metal handle.

I have said that the attachment of the scales to the tang might be any temporary or suitable attachment, as it is only necessary that they shall hold the scales and tang in their proper relation to each other until after the covering has been cast thereon. When that covering is so cast upon the parts they are firmly held together, irrespective of any connection which may have been previously made between the scales and tang.

I have illustrated the invention as applied to a knife; but it will be readily understood

by those skilled in the art that it applies to forks and like articles of table service.

I claim—

The herein-described improvement in table-cutlery, consisting in the sheet-metal tang extending from the blade, the struck-up scales upon each side the tang, and a cast-metal

covering surrounding said scales to form the surface of the handle, substantially as described.

JAMES D. FRARY.
